UNITED STATES PATENT OFFICE.

DAISY S. WARD, OF BROOKLYN, NEW YORK.

CHILD'S GARMENT.

Application filed January 18, 1928. Serial No. 247,608.

This invention relates to an under-garment intended for infants or young children, and has for its object to provide a type of supporting garment which will be provided with attaching means for diapers or other lower garments worn by the infant. Heretofore, in garments of this same general character, the child's diapers have usually been secured directly to the body of the upper garment, which is usually a shirt, band or the like. The means of attaching the diapers to such upper garment has generally consisted of safety pins, and when such fastening means are used, holes are formed in the garment which, due to the pull of the diaper, soon enlarge and cause the garment to become torn and soon unfit for use. This is particularly so where the garment to which the diaper has been attached is of knitted fabric, in which the breaking of one thread by the piercing of a safety pin, rapidly causes large holes to form.

The primary object, therefore, of this invention is to provide, in several forms of upper garments, a means of attachment for a diaper or other lower garment, which means of attachment will be so arranged and disposed, that the same not only enables the diaper to be satisfactorily held in place upon the infant, but which also avoids puncturing, or in any other way mutilating the actual body of the garment to which the diaper is adapted to be secured.

A further object of this invention is to provide such means of securing a diaper in position, which means may, if desired after considerable use, be severed or otherwise detached from the body of the garment on which they are formed, leaving the body of such garment intact and greatly extending the life of such garment.

With these objects, and such other objects as may hereinafter appear, in view, I have devised the particular arrangement of parts set forth below, and pointed out in the claim appended hereto.

Reference is to be had to the accompanying drawings forming a part hereof, in which—

Fig. 1 is a front elevation of a child's undershirt made in accordance with my invention;

Fig. 2 is a similar view showing the manner in which a diaper may be attached;

Fig. 3 is a sectional view, on the line 3—3 of Fig. 1, looking in the direction of the arrows;

Fig. 4 is a sectional view of one of the side

portions of the garment, showing one of the ways in which the securing tabs may be folded for attachment to the diaper;

Fig. 5 is a perspective view of another type of garment or band showing the manner in which attaching tabs may be formed thereon;

Fig. 6 is a sectional view on the line 6—6 of Fig. 5, looking in the direction of the arrows;

Fig. 7 is a perspective view of a garment somewhat similar to that disclosed in Fig. 5, with the exception of the fact that the same is provided with supporting shoulder straps; and

Figure 8 is a sectional view on the line 8—8 of Fig. 7, looking in the direction of the arrows.

Throughout the various views of the drawings, similar reference characters designate similar parts.

In the embodiment of my invention disclosed in Figs. 1 to 4 inclusive, I have shown an infant's upper garment in the form of an undershirt 1. The same may be of any knit, 80 or woven textile fabric and is provided with the conventional shoulder straps 2. At the lower end of the garment is provided a pair of laterally extending flaps or tabs 3 and 4. These tabs 3 and 4 extend out from the side edges or seams of the garment designated at 5 and 6. Each flap, may for the purpose of providing a substantial construction, be composed of several thicknesses or plies of material, such thicknesses of material being shown at 7 and 8 and comprising the layers of fabric which make up the front and back of the shirt. It will be seen that each of the tabs 3 and 4 is separated from the body of the garment by a continuous longitudinal seam 9. Through this construction the tabs, while made integral with the body of the garment, are maintained substantially separate therefrom, in that when the same are punctured by the safety pins 10, which

attach the diaper 11 to such tabs, any perforations or openings that may be formed in these tabs by the pins and subsequent diaper pull, will not be extended into the body of the garment. The separating seams 9 also maintain the body of the garment in its completed form so that should the tabs 3 and 4 become mutilated by the constant insertion of attaching pins 10 and diaper pull thereon, they may readily be cut off or otherwise disposed of and the garment proper will still be useful and unmutilated. The tabs 3 and 4

are shown in more or less elongated shape with their lower ends extending coextensive with the lower edge of the garment. It will be understood that these tabs may be made 5 in various shapes according to the type of garment on which they are provided and they may, if desired, be made of different or stronger material from that constituting the body of the garment. The tabs may also, if 10 desired, be provided with detachable fastening means for securing them to the garment so that they may be removed if desired and new tabs attached when those in use become worn or torn by constant use. The manner 15 in which these tabs are used is clearly disclosed in Figs. 2 to 4 inclusive. It will be seen that the same project out laterally from the longitudinal sides of the garment and are of sufficient length to enable the diaper 20 to be drawn up as high as desired, and secured at any point on these tabs as is required to properly hold the diaper in place. The folded diaper may be merely secured in place as shown in Fig. 2 by having the attaching 25 pins pass through the two folds 11 and 12 of the diaper and through the tabs. In some instances, where it is required to have the diaper fit the child more snugly than can be done by securing the diaper as shown in Fig. 30 2, the diaper may be folded in as shown in Fig. 4, and the tabs folded longitudinally as at 13, the securing pin then passing through the various folds of the diaper as well as through the doubled-over parts of the tab. 35 In Fig. 5 is shown an infant's band which may be made of either knitted or woven fabric and which has the front, wider abdominal-supporting part 14, and back portion 15. An adjusting means for enabling the garment 40 to be drawn snugly about the child's body consists of a slit 16 provided in a projecting part or tab 20 located at the front of the garment, and the end 17 of the front flap 14 is passed through the slit, thence folded back upon itself, and the two parts 14 and 45 17 are pinned together by a safety pin 19. At 21 and 22 are shown the laterally extending attaching tabs which are generally similar in principle to the tabs 3 and 4 disclosed 50 in Figs. 1 to 4 inclusive. These tabs form a substantial continuation of the body of the garment, but they are physically separated therefrom by means of longitudinal lines of stitches 23 and 24. Thus after considerable 55 use when the tabs 21 and 22 become torn from constant piercing by the attaching pins for the diaper and subsequent diaper pull, the tabs may be cut off on the outside of the lines 60 of stitching 23 and 24, leaving the body of the garment intact and capable of further use. It will be seen that the tab 22 is made up of several thicknesses of material, such thicknesses of material in this instance, comprising 65 extended parts on the front portion

14 and the back 15. The tab 21 is similarly constructed, that is, it is composed of extended parts of the flap 20 and the back 15. For the purpose of strengthening the garment, the edges of the various parts, comprising 70 the front 14, back 15 and the tabs 21 and 22, are bound by a suitable binding strip 25.

In Fig. 7 is shown a garment generally similar to the garment disclosed in Fig. 5 and the same numerals of reference are applied 75 to the similar parts. The garment shown in Fig. 7 is, however, provided with supporting shoulder straps 26 and 27, which are adjustable by being looped through slits 28 near the top edge of the front band 14. The tabs 21 and 22 disclosed in the garment of Fig. 7 are similar to those shown in Fig. 5 and are similarly separated from the body of the garment by means of the lines of dividing 80 stitches 23 and 24. The garment shown in Fig. 7 is made of several thicknesses of material or is lined with soft flannel, so that the tabs, disclosed in cross section in Fig. 8, are composed of a plurality of thicknesses of 85 folded fabric and the same are, as a result, 90 quite substantial and lasting.

From the foregoing, the manner in which my improved garments are worn and used will be readily understood. The garment disclosed in Figs. 1 to 4 inclusive, is in the form of a shirt and the manner in which the diaper is secured thereto has previously been described. The diaper may also if desired be folded in many ways according to the practice adopted by different mothers. In each instance, however, the tab will be found to project in such a way that the securing pins may be passed through it to hold the diaper in place. If the shirt is too long for very young or new-born infants, the shirt may be 105 turned up at the bottom without in any way interfering with the use of the securing tabs.

In the garments disclosed in Figs. 5 to 8 inclusive, bands are shown and the attaching tabs there shown are secured to the diaper 110 similarly to those disclosed in Figs. 1 to 4. In any of the constructions shown it will be seen that the tabs while preferably forming an integral part of the garment, are so secured to the side edges of the same that said tabs can be easily cut away when they become excessively torn from the constant insertion of the securing pins and diaper pull, leaving a garment which may be worn for some time 115 thereafter without presenting a disreputable appearance.

Having described several embodiments of my invention, it is obvious that the same is not to be restricted thereto, but is broad enough to cover all structures coming within 120 the scope of the annexed claim.

What I claim is:

A child's undergarment provided with means for attaching to and supporting a diaper, said means consisting of several tabs of 130

substantial width secured to the body of the garment and extending out laterally from the sides thereof and permitting the diaper to be attached at any desired point on said tabs and thus held in a higher or lower position of adjustment on the body according to the size of the child, the lower edges of said tabs beginning near the lower edge of the

garment body, and lines of stitching located between the tabs and the body of the garment to permit the severance of said tabs from said body without interrupting the continuity of the garment body.

Signed at the city, county and State of New York, this 17th day of January, 1928.

DAISY S. WARD.
